UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

REFRIGERATOR CONSTRUCTION.

Application filed March 25, 1925, Serial No. 18,132. Renewed July 14, 1927.

This invention relates to refrigerator construction, and has for its object a construction in which the shell of the refrigerator is a solid cast stone work of a composite material, part of which possesses heat-insulating qualities.

Another object of this invention is to eliminate the expensive and tedious carpentry work which is necessary in the construction of refrigerators in which a part of the same is cabinet work. It has been proposed before to form a refrigerator of a composite shell partly of wood and partly of stone, but the time necessary in building up the wooden part of the refrigerator is unnecessarily long and is more expensive than the construction embodied in this invention.

In the drawings:

20 Fig. 1 is a vertical section through a set of moulds for casting the inner heat-insulating refrigerator core.

Fig. 2 is a similar sectional view showing the heat-insulating core in the mould.

25 Fig. 3 shows a section through a second set of moulds in which the heat-insulating core is floated.

Fig. 4 is a perspective view of the moulded refrigerator heat-insulating core.

30 Fig. 5 is a perspective view of the completed refrigerator shell with a portion of the outer layer of stone broken away.

Fig. 6 is a vertical section through the refrigerator taken on the line 6—6 of Fig. 5.

35 The initial step in this construction is the moulding or casting of a refrigerator core which is shaped to conform with the general design of the finished product. To mould this shell I assemble the outer moulds *a* to the bottom mould *b*, and clamp the same in place by means of the long tie bolts *c*. The cores *d* are carried in any suitable manner and are spaced from the remaining portion of the mould, as is clearly shown in Fig. 1.

40 The mould is now ready to receive the material, which, when poured in the mould, as shown in Fig. 2, will form a refrigerator core *e* when allowed to set. The wood strips *f* are cast into the back of this inner core *e* shell for a purpose that will later be evident.

45 This material or mix is preferably formed by combining 60% of magnesium oxide by weight, 30% of cork dust by weight, and 10% of glue dissolved in water by weight.

50 The above mixture is made ready for pour-

ing by adding sufficient water so that the same may be readily poured into the mould. Such a material when hardened possesses relatively high heat-insulating properties, but is relatively light due to the large percentage of cork which is incorporated in the mixture. This cork also serves to make the shell heat-insulating and the magnesium oxide gives the necessary strength to the stone casting. Obviously, there are many other combinations of elements which when combined in proper proportions will give measurably good results and possess practically as good heat-insulating properties as the mix I now use. When the core is removed from the shell it will be seen by observing Fig. 4 that this shell practically corresponds to the shape of the finished refrigerator, and is provided with the food chambers or compartments *g* and the connecting passageways *h*. The mould *a* and the cores *d* are provided with ribs *i* so that when the core is removed from the moulds the grooves *j* are impressed in the walls of the core.

55 Referring to Fig. 3, this core possessing high heat-insulating properties, is now floated in the final set of moulds which comprise the outer mould *k* provided with the inner cores *m*. A cross brace or supporting beam *n* may be screwed or otherwise secured to the wooden strips *f* cast into the refrigerator insulating core and the beam correctly spaces the insulating core from the mould walls, thereby leaving a space *o* which is approximately one-eighth of an inch in depth. When this refrigerator insulating core is properly located in the finishing moulds an oxy-chloride cement is poured in the space between the core and moulds and fills up this one-eighth inch space therebetween and flows into the grooves *j* carried by the insulating core. This oxy-chloride cement is preferably composed of a mixture of magnesium chloride 25%, silica 50% and sand 25% by weight. To this is added enough magnesium chloride of 26° Bé. so as to make the mixture easy to pour. When this oxy-chloride cement is allowed to set and harden the refrigerator may be pulled from the moulds and my finished product is completed. Figs. 5 and 6 show this finished product and the outer exterior surface of the refrigerator is smooth and provides a white exterior coating for the refrigerator.

Such a refrigerator construction is in reality a composite shell structure in which the major portion is composed of a heat-insulating material provided with a covering of oxy-chloride cement which is not a good heat-insulator, the said oxy-chloride cement covering being united with said insulating core forming a solid shell structure which is strong and yet light in weight, possesses the necessary heat-insulating properties and is not easily fractured.

What I claim is:

1. In a refrigerator construction, the combination of an inner moulded shell of heat-insulating material and serving as a core, and an outer cast shell secured to and contacting with said core both on the inside and outside thereof.

2. In a refrigerator construction, the combination of an inner moulded shell of heat-insulating material and serving as a core, and an outer moulded shell cast united to said inner shell both on the inside and outside thereof.

3. In a refrigerator construction, the combination of an inner moulded shell of heat-insulating material, and serving as a core, said inner moulded shell provided with grooves formed therein, and an outer moulded shell cast about said inner shell and contacting therewith, the material of said outer shell flowing into said grooves which when hardened keys the outer shell to the inner shell.

4. In a refrigerator construction, the combination of an inner moulded shell of heat-insulating material and serving as a core, said inner shell provided with one or more food chambers, and a second shell moulded and cast-united to said inner shell and contacting therewith both on the exterior surface and on the inner surface of the one or more food chambers.

5. In a refrigerator construction, the combination of an inner moulded shell formed of a substance comprising magnesium oxide, heat insulating elements and a binder which form a shell possessing high heat-insulating properties, and an outer moulded finishing shell secured to and contacting with said heat-insulating core.

6. In a refrigerator construction, the combination of an inner moulded shell of heat-insulating material serving as a core, said material comprising a mixture of 60% of magnesium oxide by weight, 30% of cork dust by weight, and 10% of glue dissolved in water by weight, and an outer shell of oxy-chloride cement cast united with the inner insulating core both on the inside and outside thereof.

7. In a refrigerator construction, the combination of an inner moulded shell of heat-

insulating material and serving as a core, and a coating of oxy-chloride cement cast-united to the surface of said heat-insulating core.

8. In a refrigerator construction, the combination of an inner moulded shell of heat-insulating material and serving as a core, and a relatively thin outer layer of oxy-chloride cement cast-united to said insulating core.

9. In a refrigerator construction, the combination of an inner moulded shell of heat-insulating material and serving as a core, and an outer layer of non-insulating material cast-united to the surface of said heat-insulating core.

10. In a refrigerator construction, the combination of a composite moulded refrigerator shell, a portion of which is a solid moulded material possessing relatively high heat-insulating properties.

11. In a refrigerator construction, the combination of a composite moulded refrigerator shell composed of two shells cast united together one of said cast shells possessing relatively high heat insulating properties.

12. A method of refrigerator construction, which comprises the casting of an inner shell of heat-insulating material which serves as a core, the inserting of said cast inner insulating core in a mould in spaced relation with the walls thereof, and the casting of a relatively thin shell of stone about the said core and contacting therewith.

13. A method of refrigerator construction, which comprises the casting of an inner shell of heat-insulating material provided with food chambers and serving as a refrigerator core, the inserting of said refrigerator core in a mould provided with cores which are positioned in said food chambers, the said insulating core floated in said moulds for the purpose of spacing said core from the outer mould and cores carried thereby and the casting of a relatively thin layer of stone over said insulating refrigerator core.

14. A method of refrigerator construction, which comprises the casting of a refrigerator shell of heat-insulating material, and the casting of a covering about the said heat-insulating shell and contacting with both the outside and inside surfaces thereof, said covering composed of a substance which is non-insulating and possessing relatively great strength and fineness of texture.

In testimony whereof I have affixed my signature.

LLOYD G. COPEMAN.
